UNITED STATES PATENT OFFICE.

FRANK M. CORREA, OF HONOLULU, TERRITORY OF HAWAII.

ADJUSTABLE BEDDING CLAMP.

Application filed August 24, 1925. Serial No. 51,900.

This invention resides in the provision of an adjustable bedding clamp which is simple as to construction, inexpensive, capable of attachment to various styles and sizes of 5 beds and which will operate in a reliable manner to clamp and hold bedding securely in place upon a mattress.

An object of the invention is to provide an adjustable bedding clamp of the character 10 described in which there is provided a novel means for locking the clamp in adjusted position, which means is subject to an easy and quick operation and cannot be jarred or otherwise accidentally moved out of locking position.

A further object of the invention is to provide an adjustable bedding clamp of the character described which is small, compact and comparatively inconspicuous when in 20 use.

With the above mentioned and other objects in view, the invention consists in the novel construction and combination of parts 25 hereinafter described, illustrated in the accompanying drawing, and set forth in the claims hereto appended, it being understood that various changes in the form, proportion, size and minor details of construction within 30 the scope of the claims may be resorted to without departing from the spirit or sacrificing any of the advantages of the invention.

Referring to the drawing:

Fig. 1 represents a perspective view of a 35 bed clamp constructed in accordance with this invention.

Fig. 2 represents a top plan view of the clamp.

Fig. 3 represents an end elevation of the 40 clamp.

Fig. 4 represents a side elevation of the clamp.

Fig. 5 represents a fragmentary plan view 45 of a bed showing the clamp as it would appear when attached to the bed.

Fig. 6 represents a fragmentary view of one of the elements of the clamp.

The embodiment of the invention shown in 50 the accompanying drawing comprises two substantially L-shaped clamping members designated 1 and 2, formed of suitable resilient, preferably strap, metal, and adjustably fitted together. These members have 55 certain legs 3 and 4 thereof adjustably engaged with one another and the other legs

opposed and comprising upper and lower jaws 5 and 6. The jaw 6 is adapted to engage beneath a mattress whereas the jaw 5 will engage the bedding on top of the mat- 60 tress.

The leg 4 of the clamp member 1 is provided with a longitudinal slot 7 along opposite edges of which are notches 8. The corners provided on the projecting portions 9 65 are rounded as at 10. The notches on one side of the slot are out of alignment with the notches on the other side. At one end of the slot is an enlargement 11 which will permit of the insertion and removal of a head 12 on 70 a locking pin 13 carried by the leg 3 of the member 2. This member 12 is wider than the slot 7 and notches 8 except at the enlarged portion 11 of the slot. The pin 13 is adjustably mounted in a transverse slot 75 14 in the leg 3 and has an enlargement 15 on its inner side to prevent withdrawal of the pin from said slot. When the pin is adjusted so that it lies in the slot 7, the two clamping members may be moved or adjusted to bring the jaws 5 and 6 together and to force them apart. When the jaws are in the desired clamping position, the operator grasps the head 12 and pushes the pin 13 laterally 80 into the notch 8 with which it aligns, the pin sliding in the slot 14 of the member 3, and in this way locking the two clamping members in adjusted position. By having the notches on one side out of alignment with 85 the notches on the other side, provision is made for locking the clamp in a greater number of positions. When the pin 13 is engaged in one of the notches 8, the force applied to the pin by the spreading apart tendency of the two jaws 5 and 6 insures the pin 90 remaining in place. Inasmuch as the members 1 and 2 are of resilient metal, the jaws 5 and 6 will yield and this yielding of the jaws together with the locking means insures an effective clamping of the bedding 100 shown at A, on a bed B. The jaws 6 are straight but may be provided with an opening 16 whereby the mattress will extend into the opening and prevent slipping of the jaw. 105 The upper jaw 5 is provided with a similar opening 17 whereby the bedding will extend through the opening and prevent slipping of the jaw. This upper jaw may be corrugated or provided with a series of bends as 110 shown in Figs. 1 and 4, to further insure a secure clamping of the jaw with the bedding.

In addition it may be provided with protuberances as shown at 19 formed in any suitable manner, on its under side to further insure against slipping.

5 As shown in Fig. 5, two of the clamps are used at the end of the bed to hold the bedding A in position. With the jaws 6 engaged beneath the mattress and the jaws 5 on top of the bedding A, the operator, (if 10 necessary) pushes the pin 13 into the slot 7 and then depresses the jaw 5 so that the bedding is securely clamped. Following this, the pins 13 of the clamps are moved laterally into the notch 8 in registration therewith 15 and the clamps are thus locked in the desired clamping position. The particular adjusting and locking means provides for a quick and secure fastening of the clamp in position to hold the bedding in place regardless of the size of the mattress or thickness 20 of the bedding. To accommodate the raised or bead-like portion at the end of the mattress, the jaw 5 is provided with an upward curve so as to form a pocket 20. This further prevents slipping of the jaw 5 or dislodgment of the clamp as a whole.

I claim:

1. An adjustable bedding clamp comprising two substantially L-shaped clamping 30 members having certain portions adjustably engaged with one another and the other portions opposed to one another and comprising jaws adapted to engage the under side of a mattress and on top of the bedding 35 mounted on the mattress and means for locking the adjustably engaged portions of said members in adjusted position, said jaw portions having openings therein of sufficient size to permit the bedding to extend into 40 said openings, the jaw portion of the upper member being corrugated.

2. An adjustable bedding clamp comprising two substantially L-shaped clamping members having certain legs thereof adjustably engaged with one another and its other 45 legs opposed and serving as jaws to clamp one of them, the under side of a mattress and the other of them on the bedding, one of said members having a longitudinal slot in the leg

thereof which is engaged with the other 50 member, which slot is provided on opposite sides with notches and a locking member laterally adjustably mounted on the other of the adjustable legs and slidably engaged in said slot, which member is subject to 55 movement in either direction in said notches to lock the clamp in adjusted position.

3. An adjustable bedding clamp comprising annular clamping members, portions of which are adjustably engaged with one another and other portions of which are opposed and adapted to clamp upon the under side of a mattress and upon the bedding mounted on the mattress, one of said members having a longitudinal slot therein provided with notches on opposite sides of and opening into the slot, the other of said members having a slot extending transversely therein, a locking member adjustable in the last named slot and slidably engaged in the 70 slot of the first named member, which locking member is capable of movement out of the first named slot into any one of said notches and means on said locking member which means is of greater diameter than the 75 widths of said slots and notches.

4. An adjustable bedding clamp comprising annular clamping members, portions of which are adjustably engaged with one another and other portions of which are opposed and adapted to clamp upon the under side of a mattress and upon the bedding mounted on the mattress, one of said members having a longitudinal slot therein provided with notches on opposite sides of and 80 opening into the slot, the other of said members having a slot extending transversely therein, a locking member adjustable in the last named slot and slidably engaged in the slot of the first named member, which locking member is capable of movement out of the first named slot into any one of said notches and means on said locking member which means is of greater diameter than the 85 widths of said slots and notches, said longitudinal slot being enlarged at one end thereof.

FRANK M. CORREA.
